COUNTING APPARATUS

Herman Walter Gilbert, Kew Gardens, N. Y., assignor to Cutting Room Appliances Corp., New York, N. Y., a corporation of New York

Application September 20, 1939, Serial No. 295,767

3 Claims. (Cl. 235—91)

This invention relates to new and useful improvements in a counting apparatus.

The invention proposes to so support and operate a counter that it is particularly adapted to count a number of pieces cut from a roll or bolt of yard goods. In the garment industry and other industries it is necessary to cut a plurality of pieces from yard goods and superimpose them upon each other to produce a lot, upon which the various pattern pieces are subsequently placed to cut the goods in accordance with the pattern. However the operation of cutting the pieces and superimposing them upon each other is particularly tedious when done individually by hand. There are various types of machines and mechanisms capable of automatically spreading and folding layer upon layer of yard goods to obtain strip sections of desired widths and lengths superimposed upon each other, and these machines each include a counting mechanism for counting the layers which subsequently may be cut apart to produce the superimposed pieces desired. However cutting plants which cannot use spreading machines, and often on special jobs, the measuring off, cutting or tearing, and superimposing of pieces from yard goods is done manually. The counting apparatus in accordance with this invention is particularly intended to count the superimposed pieces in the later mentioned instances.

More specifically the invention proposes to characterize the counting apparatus by the fact that it is provided with a vertical member flexibly supported to move slightly rearwards when pressed at any front point with a scissor, or other cutting tool, or other implement or one's finger, or hand. Furthermore the invention makes use of a novel operating means connected with said vertical member to operate the counter to indicate the number of times the vertical member is pressed rearwards and so indirectly count the pieces of goods.

The invention proposes to construct the counting apparatus in such a way that it may be rested on a cutting table to the rear of the yard goods which is extended across the front portion of the table.

The table may be provided with usual markers so that the yard goods may be drawn across the markers and then the pieces cut manually with a scissor or other cutting implement or torn. It is proposed to so arrange the counting apparatus that upon conclusion of cutting or tearing the pieces off, the scissors or other cutting implement or finger may engage the ver-

tical member by slightly extending the cutting or tearing act, to actuate the counter, and advance it one digit.

Still further the invention proposes to construct the vertical member sufficiently high so that a large quantity of cut pieces may be superimposed during the cutting operation, while the counting apparatus is being used.

Still further the invention proposes the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

20 In the accompanying drawing forming a material part of this disclosure:

Fig. 1 is a perspective view of a counting apparatus constructed in accordance with this invention.

25 Fig. 2 is a vertical sectional view taken on the line 2—2 of Fig. 1.

Fig. 3 is a fragmentary horizontal sectional view taken on the line 3—3 of Fig. 1.

30 Fig. 4 is a transverse vertical sectional view taken on the line 4—4 of Fig. 2.

The counting apparatus in accordance with this invention includes a body 10 having a flat bottom for resting upon a cutting table or other similar body. The body 10 is of hollow construction and has a front opening 11 surrounded by a flange portion 10a. The body 10 is opened at the bottom, and along the bottom edges is provided with flange portions 10b. A plate 12 is attached across the flange portions 10b for closing the opening at the bottom of the body. At the top, the body 10 is formed with an area 10c having an opening 13 through which the numbers on the face 14a of a counter 14 are viewable. This counter 14 is of conventional construction, having a radial arm 15 which is oscillated forwards and rearwards for advancing the counter one digit. The counter 14 is mounted within the top corner of the body 10 in such a way that the reading 14a thereof is viewable through the window opening 13, and moreover so that the knob 14b by which the counter may be turned back to zero is accessible at the side of the body 10.

35 A vertical member 16 is mounted across the front opening of the body 10 and is flexibly sup-

ported to move slightly rearwards when pressed at any front point with a pair of scissors, or other cutting implement or fingers, or hand. The vertical member 16 is in the form of a flat plate. Its front face is provided with a rubber pad 17, or other pad, so as to cushion the blow which the member receives when engaged by the scissors, or other cutting tool.

The member 16 may be flexibly supported in various ways. The preferred way is illustrated, which includes a pair of lugs 18 mounted upon the rear face of the member 16 and engaged by a yoke which has its upper ends 19a outwardly directed and turnably supported in lugs 20 formed upon the material of the side walls of the body 10. The lugs 18 are arranged on substantially the vertical center of the plate 16. The yoke 19 has a central horizontal portion 19b which extends across the back of the plate 16 with its end portions freely engaging through the lugs 18. This central portion 19b then continues into side arm portions 19c which extend upwards and continue into the outwardly disposed end portion 19a previously mentioned. The yoke 19 serves to support the plate 16 in a manner so that when the plate is pressed at the top, the top portion may pivot inwards, and when pressed at the bottom, the bottom portion may pivot inwards, and when pressed at the center, the entire yoke 19 may pivot inwards.

The plate 16 is provided with several laterally projecting lug portions 16a engaging the flange portions 10a so as to prevent any portion of the vertical member moving outwards, while any other portion is moved inwards. More specifically the lug portions 16a include top lug portions which engage the top of the opening 11, and bottom lug portions which engage the bottom ends of the opening 11. These lug portions are clearly viewable in Fig. 1. It is pointed out that the lug portions 16a do not prevent any of the parts of the vertical member from moving inwards.

A means is provided for advancing the counter 14 one digit for each rearward and forward motion of the vertical member 16. This means includes a pair of converging links 21 and 22 pivotally connected together by a pintle 23 at adjacent rear ends, which ends are located directly behind the central portion 19b of the yoke 19. The links 21 and 22 extend towards each other. The forward ends of the converging links 21 and 22 are pivotally connected with lugs 21' and 22' respectively, mounted upon the inner face of the vertical member 16. The pintle 23 also supports a connector link 24 which extends rearwards, see Fig. 2.

The rear end of the connector link 24 is pivotally connected with an intermediate portion of a vertically extending lever 25. This lever is pivotally supported by a pintle 26 upon a bracket 27 located midway between the link 24 and the bottom of the body 10. The upper end of the lever 25 is pivotally connected with an arm 28 which has its other end pivotally connected with the arm 15 of the counter 14. Resilient means, in the form of a spring 29, is connected between the lower end of the lever 25 and a stationary screw 30 mounted on the body 10, acting to normally and resiliently urge the vertical member 16 forwards, so that the lugs 16a engage the flange portion 10a.

A clapper 31 is mounted upon the arm 15 and is adapted to strike a bell 32 mounted on the

body 10 so as to produce an audible signal which may be heard when the arm 15 is moved sufficiently rearwards to register a digit on the counter 14.

5 The operation of the device is as follows:

The cutting apparatus is placed on a cutting table, or other object. The goods to be cut or torn into pieces, is drawn across the table and measured off by customary markers mounted on the table. With a scissor or other implement, or the fingers, each piece of yard goods is cut or torn by starting from the front edge and cutting or tearing towards the rear edge. The cutting apparatus is so placed that when the pieces are cut or torn, the scissors or one's finger or hand strikes the vertical member 16 moving it inwards.

10 The various pieces of yard goods which have been cut and stacked, one upon the other, determines the elevation at which the uppermost piece is cut. The vertical member 16 is of suitable height so that a high stack may be cut, and counted with the cutting apparatus. Heretofore when these pieces were cut manually it was customary for the cutter to try to keep count of the same, which very often proved a physical impossibility, since the cutter's mind would be detracted by other persons, or some other detraction would occur.

15 As a result after a stack of pieces were cut, the cutter would now take to manually counting the pieces of the stack, requiring several recounts since the cut pieces have a tendency of striking together, and there is always the possibility of the count being incorrect.

20 Each time the vertical member 16 is engaged by a cutting scissor, or other implement, or finger or hand, the vertical member 16 will move rearwards. This rearward motion may comprise merely the top portion moving rearwards, or the bottom portion moving rearwards, while other portions pivot about certain of the lugs 16a as a pivot. Or if the vertical member is engaged at the center the entire vertical member may move rearwards. Irrespective of the manner in which the vertical member 16 moves rearwards, the motion will be transmitted by the link 24 to the lever 25 so as to move the upper portion of the lever rearwards. This motion is transmitted by the arm 28 to the arm 15 of the counter 14 which registers another digit. When the scissor, finger, or other implement is drawn off from the vertical member 16, the spring 29 will automatically return the vertical member to its front position and will similarly return the arm 15 of the counter 14 back to its initial position so that the counter is now ready to count another digit.

25 The audible signal comprises the clapper 31, and bell 32, and is used for the purpose of insuring the proper operation of the counter. When the operator does not force the vertical member 16 sufficiently rearwards to have the counter register, the clapper 31 will not engage the bell 32.

30 It should be recognized that the main feature of the counting apparatus resides in the fact that it counts the cut or torn pieces which are being cut and stacked from yard goods.

35 While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I

claim as new and desire to secure by United States Letters Patent is:

1. In a device of the class described, a hollow body for resting on a cutting table or other object and having a front opening, a counter mounted on said body so as to be viewable and having an operating radial arm movable to and fro for each digit advance, a vertical member extending across said front opening, means for resiliently holding said vertical member in a forward position, a yoke pivotally mounted within said body and pivotally connected with a central part of said vertical member, converging links pivotally mounted at their front ends on said vertical member on opposite sides of said central part and having their rear ends pivotally connected together, a connector link pivotally mounted on the rear ends of said converging links, a lever pivotally connected intermediate of its ends with said connector links, an arm connecting one end portion of said lever with said operating radial arm, and means for pivotally holding the other end portion of said lever.

2. In a device of the class described, a hollow body for resting on a cutting table or other object and having a front opening, a counter mounted on said body so as to be viewable and having an operating radial arm movable to and fro for each digit advance, a vertical member extending across said front opening, means for resiliently holding said vertical member in a forward position, a yoke pivotally mounted within said body and pivotally connected with a central part of said vertical member, converging links pivotally mounted at their front ends on said vertical member on opposite sides of said central part and having their rear ends pivotally connected together, a

5 connector link pivotally mounted on the rear ends of said converging links, a lever pivotally connected intermediate of its ends with said connector links, an arm connecting one end portion of said lever with said operating radial arm, and means for pivotally holding the other end portion of said lever, comprising a bracket stationarily mounted within said body, and a pintle pin connecting said bracket and said lever.

10 3. In a device of the class described, a hollow body for resting on a cutting table or other object and having a front opening, a counter mounted on said body so as to be viewable and having an operating radial arm movable to and fro for each digit advance, a vertical member extending across said front opening, means for resiliently holding said vertical member in a forward position, a yoke pivotally mounted within said body and pivotally connected with a central part of said vertical member, converging links pivotally mounted at their front ends on said vertical member on opposite sides of said central part and having their rear ends pivotally connected together, a connector link pivotally mounted on the rear ends of said converging links, a lever pivotally connected intermediate of its ends with said connector links, an arm connecting one end portion of said lever with said operating radial arm, and means for pivotally holding the other end portion of said lever, said means for resiliently holding said vertical member comprises a spring connected with said lever and urging it to move said links forwards, and means for limiting the vertical member from moving further forwards than certain points with relation to said body.

35 HERMAN WALTER GILBERT.
